CLAIM

The ornamental design for a wheel, as shown and described.

DESCRIPTION

FIG. 1 is a front perspective view of a wheel;
FIG. 2 is another front perspective view of the wheel;
FIG. 3 is a front view of the wheel;
FIG. 4 is a rear view of the wheel;
FIG. 5 is a rear perspective view of the wheel; and,
FIG. 6 is a side view of the wheel, wherein the top and
bottom views of the wheel are identical thereto and the
opposite side view of the wheel is a mirror image thereof.
All broken lines illustrate subject matter, structure, and/or
features of the wheel that form no part of the claimed design.
The dot-dash broken lines illustrate the bounds of the claim
and form not part of the claimed design.
